LUMINAIRE

Edmund L. Izzi, 4385 Lansing Drive,
North Olmsted, Ohio

Filed Apr. 26, 1962, Ser. No. 69,858

Term of patent 14 years

(Cl. D48—31)

Fig. 1.

Fig. 2.

Fig. 3.

Fig. 4.

FIG. 2 is a side elevational view thereof;

FIG. 3 is a front elevational view thereof as seen from the left of FIG. 2;

FIG. 4 is a rear elevational view thereof as seen from the right of FIG. 2; and

FIG. 5 is an enlarged perspective view of the luminaire of FIG. 2 with the fragmentary portion of a light support arm shown in dotted lines for illustrative purposes only.

The dominant features of my design reside in the portion shown in full lines.

I claim:

The ornamental design for a luminaire, substantially as shown and described.
